CLAIM

The ornamental design for a wide angle lighthead, as shown and described.

DESCRIPTION

FIG. 1 is a front perspective view of a wide angle lighthead; FIG. 2 is a rear perspective view of the wide angle lighthead; FIG. 3 is a front side view of the wide angle lighthead; FIG. 4 is a top plan view of the wide angle lighthead; FIG. 5 is a bottom view of the wide angle lighthead; FIG. 6 is a right side view of the wide angle lighthead, the opposite left side view being identical; and, FIG. 7 is a rear view of the wide angle lighthead.

The broken lines shown in the figures represent portions of the wide angle lighthead that form no part of the claimed design.
